US00D927456S

(12) **United States Design Patent** (10) **Patent No.:** **US D927,456 S**
Paterson et al. (45) **Date of Patent:** **** Aug. 10, 2021**

- (54) **MICROPHONE BOOM FOR A COMMUNICATIONS HEADSET**
- (71) Applicant: **Plantronics, Inc.**, Santa Cruz, CA (US)
- (72) Inventors: **Nicholas W Paterson**, Aptos, CA (US); **John A Kelley**, Santa Cruz, CA (US)
- (73) Assignee: **Plantronics, Inc.**, Santa Cruz, CA (US)
- (**) Term: **15 Years**
- (21) Appl. No.: **29/730,828**
- (22) Filed: **Apr. 8, 2020**

Related U.S. Application Data

- (62) Division of application No. 29/641,325, filed on Mar. 21, 2018, now Pat. No. Des. 882,544.
- (51) **LOC (13) Cl.** **14-01**

(57) **CLAIM**

The ornamental design for a microphone boom for a communications headset, as shown and described.

DESCRIPTION

FIG. 1 is a top-right perspective view of a microphone boom for a communications headset showing my new design;
FIG. 2 is a bottom-left perspective view thereof;
FIG. 3 is a front view thereof;
FIG. 4 is a back view thereof;
FIG. 5 is a right side view thereof;
FIG. 6 is a left side view thereof;
FIG. 7 is a top view thereof; and,
FIG. 8 is a bottom view thereof.

The broken lines depicting a temple pad, headband and earcup are to show environment and form no part of the claimed design.

1 Claim, 8 Drawing Sheets

US D927,456 S
